UNITED STATES PATENT OFFICE.

FREDERICK JOHN TURNER AND JOHN EDWARD ERNEST STARCK, OF ELSTREE, ENGLAND, ASSIGNORS OF ONE-FOURTH TO JOHN RICHARDSON CRAIG, OF LONDON, ENGLAND, AND ONE-FOURTH TO PERCIVAL JAMES PACKMAN, OF Highbury, London, ENGLAND.

RECORD AND THE MANUFACTURE THEREOF FOR TALKING MACHINES.

No Drawing. Application filed June 7, 1924, Serial No. 718,673, and in Great Britain June 19, 1923.

This invention relates to sound records for talking machines of the type wherein the record surface material is carried upon a laminated body or support consisting of a plurality of sheets of a paper-like character cemented together by an adhesive or binding material.

It has been proposed to form records of the above type consisting of a record surface material of shellac composition coated or dusted on to a sheet of hard paper which was placed face downwards on a heated matrix and a body portion formed of a plurality of sheets of paper alternating with layers of plastic composition placed on the back of the record surface sheet, the body sheets being prepared in substantially the same manner as the record surface sheet, using a cheap or inferior composition instead of the expensive shellac composition. The several prepared sheets were then united by heat and pressure.

The object of the present invention is to provide a durable record which, while capable of manufacture at a low cost, possesses an improved sound-recording surface which renders reproduction of the recorded matter more faithfully, with better tone and with the accompaniment of less extraneous noise or scratching sound.

By aid of the invention the manufacture and production of records is considerably simplified and thin and comparatively flexible records may be produced with attendant advantages as regards weight, space occupied and liability to damage.

In order to secure the desired results it has been found necessary to employ a record surface material in preformed thin sheet form having the qualities and mechanical or physical characteristics exemplified by a non-inflammable and non-resinous cellulosic material, such as cellulose acetate, which may be heated to relatively high temperature without risk of material chemical change and according to this invention materials of the form and nature above specified are essentially employed.

The adhesive or binding material em-

ployed in producing a record according to 50 the invention may be the same in basis as that of the record surface in an appropriate state for the purpose in view, or such may be of a different or cheaper material providing such possesses substantially similar 55 mechanical or physical characteristics.

It is to be understood that the material employed is used as an adhesive or binder as distinct from a filling agent or material intended to increase or form a substantial 60 part of the thickness of the record.

Record surface material in preformed thin sheets of the kind above referred to as, for example, cellulose acetate, is known for the production of sound records for talking machines and various proposals have, from time to time, been made in respect to the mounting of such upon a body or support such as a sheet of paper, cardboard, plywood or other fibrous material, or upon a comparatively thick preformed base of asphaltic nature with or without a layer of paper or cardboard incorporated in the mass and with a sheet of paper interposed between the mass or base to prevent the latter from disturbing the record surface during the impression process and as a uniting wafer or agent.

It has also been proposed to employ an adhesive or binding material of a similar 80 character to the record surface material above described for cementing the surface sheet to the body.

Such proposals as above may have met with more or less success but do not produce a record of the quality or nature of that achieved by the present invention, according to which the laminated body or support is formed of a plurality of sheets of a porous and absorbent paper, such as blotting paper, united together by a binding material of the nature specified, permeating the sheets throughout so that the laminations are formed into a practically integral body with a record surface material of the 90 nature and in the form specified above applied thereto.

The invention consists in a method of

making a sound record of the type described consisting in treating a plurality of sheets of a porous and absorbent paper with binding material of the kind described so that they may be thinly cemented together, providing a sheet or sheets of recording surface material of the form and nature specified, assembling said paper and record surface sheets and impressing a matrix (or matrices) upon the record sheet (or sheets) under pressure and at a temperature adapted to incorporate or amalgamate the whole as a practically integral body.

The invention also comprises a method of manufacturing sound records of the type described consisting in providing record surface material of the nature and form specified, providing a plurality of sheets of porous and absorbent paper with a thin coat or layer of binding material so as to leave a porous layer beneath the coating, including a plurality of coated sheets of paper between two outer sheets of record surface material and impressing a matrix (or matrices) thereon at a temperature adapted to drive out the volatile constituent of the materials employed and to cause the binding material to unite the sheets together and thoroughly to impregnate each paper sheet so that a practically integral record is formed with binding material permeating the whole body.

The invention further comprises a method of manufacturing sound records of the type described consisting in preparing a laminated body treated with binding material of the kind described, placing such body between record surface sheets of the nature and form specified and impressing a matrix upon the record surface material at a temperature of the order of 290° F.

In referring to record surface material or surface sheets it is to be understood that such terms include a record surface sheet in which the sound record is formed for each side of a record, or in the case of so-called "single-sided" records a backing sheet should be of substantially the same thickness and general nature as a sheet intended to receive a record groove although such may be of a cheaper material or make.

The material generally known as "non-inflammable celluloid" has been found suitable both as a base for the adhesive or binding material and for the recording surface sheet (or sheets). This material is known as a commodity in sheet form and sheets of an appropriate thickness, such as 5/1000ths of an inch, are procurable and may be appropriately employed and treated according to the invention.

Alternatively, a very similar raw material may be manufactured as follows:—200 parts of cotton cellulose (about 5 per cent moist) is treated with a mixture of 800 parts of

glacial acetic acid and 20 parts of concentrated sulphuric acid. This solution is treated with 400 to 500 parts of acetic anhydride, this being added progressively while agitating the solution at atmospheric temperature, say 62° F. As soon as the solution is complete water is run in while still agitating. The thin precipitate (cellulose acetate) is washed and pressed and can be moulded or set into blocks and when sufficiently seasoned sheets down to 5/1000ths of an inch in thickness can be cut therefrom.

Any appropriate colouring matter may be added to the solution of cellulose acetate, such as could be dissolved or suspended in the solution or solvents.

By moulding the cellulose acetate in a special manner sheets of, say, 3/1000ths of an inch may be prepared. Sheets of this fineness may be produced by moulding the cellulose acetate in cylindrical moulds of slightly larger diameter than that of the disc records to be made. The moulding of the material in cylinders of comparatively small diameters makes it possible to operate thereon by aid of a guillotine having a short stiff knife to produce sheets or films of approximately 3/1000ths of an inch in thickness.

It is preferred to incorporate the inner body with the recording surface material while imposing a sound record (that is to say, a record groove or track) upon the recording surface material by the aid of a matrix under pressure, and such treatment should be carried out at a temperature such as will ensure the expulsion of the bulk of the solvents from the compositions employed and cause the recording surface material to become hardened and toughened after treatment, while at the same time the coating of binding material is driven into porous sheets thoroughly to impregnate such.

It is thought that the employment of laminated porous material for the inner body plays an important part in the production of a satisfactory sound record as the porous layer under the binder coat or layer in the material permits, or provides a path for, the escape of the solvent gases and enables a high temperature (as, for example, in the neighbourhood of 290° F.) to be successfully employed.

In recording sound waves it has been proposed to reduce the depth and width of the sound wave track for the purpose of lessening the surface scrape in reproduction. Such expedients, however, have a tendency to reduce the volume of the sound. The use of the surface employed in the present invention considerably reduces the surface scrape and it therefore becomes possible to revert to deeper grooves or tracks. This might be accomplished by the use of a

thicker outer surface sheet of recording material but to obviate thus increasing the thickness (and quantity) of material to accommodate the required depth of groove or track, it has been found that if a sheet of recording surface material, of say 3/1000ths of an inch thick, is employed in conjunction with a film or layer of india-rubber solution or other plastic body which is adapted to act as a cushion and as an adhesive or binder, interposed between the outer surface of the inner body and the recording surface sheet, a deep sound wave groove or track may be produced in the latter. The interposed cushion enables the thin recording surface sheet readily to be driven in the groove of the matrix in the process of pressing and hardening as the cushion supports and backs up the sheet, ensuring a perfect impression contact. In some cases the cushion may enable the track or groove to be formed by depressing the bottom thereof slightly out of the plane of the surface sheet, that is to say so that the reverse of the sheet would disclose or show the impression or an indication of the sound groove or track.

In carrying the invention into effect according to one convenient mode by way of example, paper, pulp, hygroscopic but substantially free from extraneous or bituminous matter, is made in wet or sheet form such being soft, absorbent and of a uniform thickness. These sheets, for example, should be in the neighbourhood of 17½" x 22½" and of a thickness that causes the sheets to weigh, say 27-30 lb. to the ream, but it is preferred to employ rolls of web 10½" or 12½" wide of a corresponding thickness. While it is desirable to manufacture or have manufactured sheets of the above nature, it is possible to procure upon the market sheets of absorbent and porous paper in the nature of blotting paper which may be found to serve the required purpose if free from chemical, water-marking acid or other injurious matter.

The absorbent sheets may be cut to the desired shape in the first instance or the coated sheets or a laminated body made of such sheets may be stamped.

The sheets are coated or partially impregnated on each side with an adhesive or binding material so as to have an inner layer which is porous and substantially free from the binding material which should be a solution in an organic solvent (such as amyl acetate or alcohol, benzine or a mixture of the two or amyl acetate and chloroform), of cellulose acetate, either procured as a finished product or according to the method of manufacture above described.

The binding material should be of a consistency such as will enable it to be conveniently spread or coated upon the sheets to

provide a thin layer or film of the binding material upon each side thereof. Alternatively, the adhesive or binding material may be prepared in separate films by running or spreading a thinner solution upon a glass sheet, allowing it to set and stripping it from the glass in the form of a film or tissue suitable for interposing between the sheets of the inner body or between the inner body and the surface material.

The coated sheets are allowed to dry or season for not less than 10 minutes until a considerable portion of the solvent of the binding material has evaporated. When suitably dried a number of the sheets according to the thickness it is desired the finished record should possess (for example, four or five may be employed to produce a record in the neighbourhood of 1/32nd of an inch thick) are taken and placed together one upon the top of the other. Assuming that a recording surface is required upon both sides of the disc, two seasoned sheets of recording surface material of about 5/1000ths of an inch in thickness are procured and placed one upon either side of the pile of coated sheets which form the inner body. The inner and outer sheets are registered and placed in a suitable press between the matrices of any suitable known kind for impressing a sound wave groove or track. These are heated by any appropriate heating means to a temperature up to 290° F. The pressure at which the printing or pressing of the record is performed makes it possible to print from a light shell matrix which need not be "backed" for strengthening purposes. A perfectly satisfactory record has been produced at an ultimate pressure so low as 250 lb. to the square inch. The solvent gases appear to be driven off as the pressure is gradually increased at or about and during the reduction of the temperature as aforesaid. For example, the press may be closed on the backs of the matrices at about 100 lb. to the square inch and after an interval of, say, five seconds the pressure is gradually but rapidly increased to approximately 250 lb. This action obviates any possibility of imprisoning any of the escaping vapours of the solvent so often occurring in the process of printing where a high pressure (usually uncontrollable) is necessary, such pressure frequently exceeding twelve thousand pounds to the square inch, a pressure that does not conduce to the serviceable life of a matrix even if strengthened and supported. The pressure and temperature are maintained for a period of, say, from one to five minutes (depending on the nature of the means for cooling the press) or for a sufficient duration to cause the solvents both in the binding material and the recording surface sheets to be

115
120
125

driven off to an extent such that the surface material becomes hard and tough and rendered suitable for sound reproduction under the action of a stylus.

5 It should be observed that it is not necessary to retain the matrices and the record in the press until they are quite cold. The matrices and the enclosed record may be removed together from the press (at a temperature almost too high to lift them by naked fingers) and then placed between two cold plates, the matrices and contained record being thus very quickly cooled. When cold, the matrices can be easily and quickly 10 separated from the surface of the pressed record by the act of applying a slight pressure by hand.

It is thought that the temperature to which the recording body, including the surface sheets, is subjected, which is such as to render plastic or almost liquefy the external element, fails to destroy the substance of the materials treated owing to escape of the solvent gases through the porous strata provided by the laminated sheets of the inner body. The heat and comparatively low pressure treatment causes the record surfaces to bear a perfect replica of the matrices and a sound record is produced in which the surface is hardened and toughened to a degree that renders it more or less wear-proof while at the same time being perfectly smooth and free from scratching noise under the action of the stylus.

35 According to a modification, it is possible to make record blanks according to the above process, in which case instead of pressing the record material between matrices, plain surface elements are employed for the pressing and heating process, the temperature being maintained well below that specified when it is desired to produce the finished sound record. The blanks thus formed may be stored for future use. A sound record 40 may be impressed by pressure and heat treatment between matrices when the temperature would be raised to the neighbourhood of 290° F. In order satisfactorily to impress a sound record upon such blanks it is necessary in order to achieve the best results to reheat them at a comparatively low 45 temperature in an atmosphere of the solvent vapours or otherwise subject them to hot vapours of the solvent.

50 55 Where it is required to produce a record with a sound impression upon one side only the laminated inner body may be provided with a recording surface sheet as hereinbefore described and with a backing of the same or inferior material of suitable tension which may be applied either in sheet form or after the pressing operation the 60 backing may be coated or deposited thereupon by any suitable known process.

The sound records made according to this invention may be finished off by perforating the centre of the disc, trimming the peripheral edge and, if necessary, sealing such.

When employing surface sheets of, say, 3/1000ths of an inch in thickness the outer surface of the inner body is coated with a thin layer of rubber solution which may be applied by means of a brush or a wad of cotton wool or flannel or, if a very thin solution of rubber is employed, this may be run on to the outer surface of the inner body. The rubber solution may be such as is used for patching rubber tyres and if the marketed commodity is too thick it may be thinned with a few drops of benzine or petrol.

80 The coating of rubber is allowed to dry until it becomes slightly "tacky." When the inner body with the rubber coating is in a suitable state the thin sheet of recording surface material which may be prepared as hereinbefore described is placed over the rubber coating and the matrix is applied according to the method detailed above. The heat and pressure by aid of the rubber cushion causes the material of the thin sheet to be driven into the groove of the matrix, the heat and pressure more or less vulcanizing the rubber operating as a cement between the inner body and the recording surface material. Thus the surface sheet, the rubber cushion and the inner body are amalgamated. In the process of heating and pressing the solvent of the rubber is expelled with the volatile gases from the surface material and the adhesive or binding material of the inner body.

90 95 100 When employing the rubber cushion it is found possible to dispense with the adhesive or binding material between the recording surface material and the adjacent surface of the porous inner body. When employing the surface material in the thinner sheet form indicated, the paper or material used for the inner body may be of a somewhat lighter nature, that is to say sheets of the weight of 27 lb. to the ream may be advantageously employed.

105 Having now described our invention, what we claim as new and desire to secure by Letters Patent is:—

binding material to unite the sheets together and thoroughly to impregnate each porous and absorbent sheet so that a practically integral record is formed with the binding material permeating the whole body. 5
2. A flexible sound record for talking machines comprising, a record surface in pre-formed thin sheet form of a non-inflammable and non-resinous cellulosic material and a 10 laminated body portion on which the record surface is mounted consisting of a plurality of sheets of porous and absorbent paper which have been coated with an adhesive and binder comprising a solution of non-inflammable and non-resinous cellulosic material and heat treated at a temperature such as to drive the adhesive and binder through the absorbent and porous sheets so that it integrally incorporates and amalgamates the whole. 15
3. A method of making a flexible sound record consisting in providing preformed thin sheets of record surface material of a kind which is flexible, non-inflammable and 20 non-resinous, providing a plurality of sheets of porous and absorbent paper for forming a laminated inner body, thinly coating each of the porous and absorbent sheets with an adhesive and binding material comprising a 25 solution of a non-inflammable non-resinous material which remains flexible when dry, including the assembled coated sheets between two record surface sheets and impressing matrices thereon at a temperature 30 adapted to cause the adhesive and binding material to unite the coated sheets together and thoroughly to impregnate each sheet so that a practically integral record is formed with the adhesive and binding material permeating the whole body. 35
4. A method of making sound records for talking machines consisting in employing a record surface of thin sheets of non-inflammable and non-resinous cellulosic material, 40 forming a laminated inner body of a plurality of sheets of porous and absorbent paper thinly coated with an adhesive and binder comprising a solution of a non-inflammable and non-resinous cellulosic material and 45 heat treating the assembled sheets under pressure and at a temperature adapted to drive the adhesive and binding material through the paper so that the adhesive and binding material not only cements the sheets together but permeates and amalgamates the whole. 50
5. A method of making sound records for talking machines consisting in employing a record surface of thin sheets of non-inflammable and non-resinous cellulosic material, 55 applying a thin coat of an adhesive and binder comprising a solution of a non-inflammable and non-resinous cellulosic material to a plurality of sheets of porous and absorbent paper to form a laminated inner body and heat treating the assembled sheets under pressure and at a temperature adapted not only to cement the sheets together but to drive the adhesive and binding material through the sheets and amalgamate the whole together. 60
6. A method of making sound records for talking machines consisting in employing a record surface of thin sheets of non-inflammable and non-resinous cellulosic material, 65 applying a thin coat of an adhesive and binder comprising a solution of a non-inflammable and non-resinous cellulosic material to a plurality of sheets of porous and absorbent paper to form a laminated inner body and assembling the porous sheets and record surface material together and impressing a matrix upon the latter at a temperature adapted to cement the porous sheets and drive the adhesive and binding material through them and amalgamate the whole together. 70
7. A method of making sound records for talking machines consisting in employing a record surface of thin sheets of non-inflammable and non-resinous cellulosic material, 75 applying a thin coat of an adhesive and binder comprising a solution of a non-inflammable and non-resinous cellulosic material to a plurality of sheets of porous and absorbent paper to form a laminated inner body and assembling the porous sheets between two sheets of record surface material and impressing a matrix upon each sheet at a temperature adapted to cement the porous sheets and drive the adhesive and binding material through them and amalgamate the whole together. 80
8. A method of manufacturing sound records of the type described, consisting in 85 providing a record surface of thin sheets of non-inflammable and non-resinous cellulosic material, thinly coating a plurality of sheets of porous and absorbent paper with an adhesive and binder comprising a solution of a non-inflammable and non-resinous cellulosic material so as to leave a porous layer beneath the coating adapted to provide a path for the escape of the volatile gases, including a plurality of the coated sheets between two outer sheets of record surface material and impressing matrices thereon at a temperature adapted to drive out the volatile constituents of the materials employed and to cause the adhesive or binding material to unite the sheets together. 90
9. A method of making a sound record for talking machines which comprises 95 assembling sheets of a porous and absorbent paper which have been previously treated with an adhesive and binding material, applying a layer of cushioning material, such as rubber, to the outermost of said

sheets, applying record surface material in the form of preformed thin sheets to said cushioning layer so that the layer lies between the porous and absorbent sheets and the record surface material, and heat-treating the assembled record blank between matrices at a high temperature adapted to incorporate the whole together.

10. A sound record for talking machines comprising a thin (such as 3/1000ths of an

inch) sheet of a record surface material of the nature and form specified, a laminated body and a thin cushioning layer (such as rubber) between the record surface material and the laminated body. ¹⁵

In testimony whereof we have signed our names to this specification.

FREDERICK JOHN TURNER.
JOHN EDWARD ERNEST STARCK.
